(57) **CLAIM**

We claim the ornamental design for a belt support apparatus, as shown and described.

DESCRIPTION

FIG. 1 is an isometric top, left view of the belt support apparatus;

FIG. 2 is an isometric top, right view thereof;

FIG. 3 is a left view thereof;

FIG. 4 is a right view thereof;

FIG. 5 is a top view thereof;

FIG. 6 is a bottom side view thereof;

FIG. 7 is a front view thereof;

FIG. 8 is a back view thereof; and,

FIG. 9 is a isometric top, left view of the belt support apparatus on a belt thereof.

The broken line showing of a belt is included for the purpose of illustrating environmental matter and forms no part of the claimed design.
